METHOD AND APPARATUS TO ENABLE SWIMMERS TO CONVERSE UNDER WATER

Walter N. Wainwright, Waterford, Conn., and Russell I. Mason, Barneveld, N.Y., assignors to the United States of America as represented by the Secretary of the Navy

Filed July 14, 1959, Ser. No. 827,128

5 Claims. (Cl. 340—5)

(Granted under Title 35, U.S. Code (1952), sec. 266)

The invention described herein may be manufactured and used by or for the Government of the United States of America for governmental purposes without the payment of any royalties thereon or therefor.

This invention relates to underwater voice communication and more particularly to a method and apparatus to enable two or more divers or underwater swimmers to confer readily with one another or with personnel aboard a nearby vessel.

A team of divers or underwater swimmers, referred to as swimmers hereinafter, working together under water are severely handicapped if they are not able to confer in the same manner as a team of men working together in air. Swimmers can function more safely and more efficiently if they are enabled to converse as readily as they can in air or over an even greater range than they can in air.

An object of this invention is to provide a method and apparatus for swimmers to enable them to continuously confer while submerged, just as well as they might confer in air, without manipulating any controls, over a distance ranging from bodily contact to several hundred feet apart, not requiring bulky or weighty encumbrances, and without electrical lead connections therebetween so as not to interfere with their freedom of movement under water.

A further object is to provide a compact, light-weight apparatus for a swimmer, for raising his sensitivity to waterborne voice sounds far above that traceable to waterborne sounds detectable by his bone structure and transferable, thereby to his auditory nerve.

Other objects and many of the attendant advantages of this invention will be readily appreciated as the same becomes better understood by reference to the following detailed description when considered in connection with the accompanying drawing wherein:

FIG. 1 shows a swimmer equipped in accordance with this invention, and

FIG. 2 is a block diagram of an embodiment of this invention excluding the mask into which the swimmer speaks.

There are three factors that limit underwater voice communication. One factor is the impedance mismatch between the voice mechanism and the water plus the fact that increased ambient pressures adversely affect the voice; however, the effects of changes in ambient pressures on the voice are small in comparison to the effects produced by impedance mismatch. If a mask is provided around the swimmer's mouth to enable him to form words and speak, the intensity of the voice energy that enters the water is greatly reduced as a result of the impedance mismatch. Since ρc of air is 42 and the ρc of salt water is 154,000, an increase in pressure of approximately 60 times is required for the human voice to produce the same amount of power in water as in air. Power developed under water by shouting loudly into a mask supported around the mouth is approximately equal to that produced in air by reading audibly but at a soft vocal level. For the most part, vocal energy that is delivered by a swimmer to the water is liberated by surface portions of his body, such as his head, neck, chest, and back which are more closely matched to the water than his voice

2

mechanism in the mouth. This is particularly evident when the swimmer shouts into his mask.

Noise generated by breathing apparatus is a second factor that limits underwater voice communication. A 5 open circuit self contained breathing apparatus generally utilizes compressed air which is contained in high pressure cylinders worn by the swimmer. Breathing is accomplished by inhaling compressed air through a demand regulator and exhaling directly into the water theret 10 generating a great deal of noise. A closed circuit self contained breathing apparatus generates substantially less noise than an open circuit apparatus. It utilizes oxygen instead of compressed air and breathing is accomplished by inhaling the gas that includes a predetermined percentage of oxygen and exhaling the exhaust through a canister that absorbs carbon dioxide. The purified gas with the addition of oxygen as needed, is recirculated. 15 An exhaust gas is liberated into the water. Far less noise is generated by closed circuit breathing apparatus, but nonetheless this noise level may interfere with voice communication.

A third factor that limits underwater voice communication is that human hearing under water by way of the natural hearing mechanism is negligible compared to that 20 in air. For a given sound pressure at a given frequency under water, the amplitude of particle movement is a tiny fraction of particle movement in the air for the same sound pressure or frequency. The structure of human ears are such that they are properly coupled, mechanically, to air. Since the basic mechanism of hearing depends on the amplitude of movement of the ear drum and since particle movement in water for sound pressure and frequencies corresponding to human conversation is negligible compared to the particle movement in air, 25 human being that relies on his natural hearing mechanism under water is to all intents and purposes effectively deaf. There is substantial evidence to indicate that most of the energy of underwater sound is transmitted to the hearing mechanism, not by way of the ear drum, but by conduction 30 through the bones of the body, particularly the skull as in the case of persons who are deaf as a consequence of ear drum defects. Under water, a swimmer with healthy ear drums and auditory nerve is nearly as deaf as the swimmer that lacks ear drums, but has healthy 35 auditory nerves.

A method in accordance with this invention for enabling a team of swimmers to continuously confer under water despite the above described difficulties requires that each swimmer be provided with a mask for defining 40 an air space at least around his mouth and also requires that his breathing apparatus be not of the type where the swimmer must grip an air inlet part with his teeth. Self contained breathing apparatus including a breathing mask with a demand regulator is marketed commercially. 45 In U.S. Patent 2,456,130, there is shown a breathing mask including securing straps, viewing window, and valve means for passing gases of inhalation and exhalation suitable for use in carrying out the principles of this invention. The mask is essential because with it the swimmer is able to open his mouth into an air space to form words and to speak and shout. Also, the swimmer is provided with a breathing air supply that may feed into his mask or into his nose. The method also requires that substantially all of the surface area of the swimmer's 50 head, mask, chest, and back, be exposed to the water, or where the swimmer must wear a cold weather suit the method requires the next best thing, namely, that the above-mentioned surface area of the swimmer's body not be covered with pressure release or sound isolating material. At each swimmer, the method includes the 55 steps of continuously intercepting and extracting from the water a fraction of any vibrational energy in the

er in the voice frequency range, amplifying the extended energy, continuously transferring the amplified voice frequency vibrational energy to the auditory nerve of the swimmer, continuously providing an air space around the swimmer's mouth into which he may speak currently while listening to voice frequency energy, continuously providing a breathing air supply to the swimmer. For better results with the above method, voice frequency vibrational energy is intercepted and extracted from the water at a point that is spaced from the swimmer's breathing air valves and from the swimmer's wing limbs whereby, of the noise generated by the breathing supply and by the strokes of the swimmer's arms and the kicks of his feet the percentage that is intercepted, extracted from the water, and amplified is maximized. Satisfactory results have been obtained by intercepting and extracting vibrational voice frequency energy from the water adjacent the pelvic region of the swimmer.

The apparatus, not shown, for carrying out the method includes hollow ear plugs which connect to thin walled compliant hollow rubber balls or to a short broad horn with two horns respectively for directional response) whose ends are covered by a thin compliant membrane of low mass and inertia and which has many times the area of the ear drum. For purposes of pressure equalization, the ear drum side of the thin compliant member is sealed to the breathing air supply.

Another apparatus for carrying out the method includes a small underwater transducer 10 sensitive to vibrational voice frequency energy. Some transducers sensitive to the voice frequency range are too cumbersome for this purpose. A crystal contact microphone of the type used on stringed instruments is one example of an electroacoustic transducer that is sufficiently sensitive and small enough to be supported comfortably adjacent the swimmer's pelvic region. It is supported with its sensitive surface in contact with the water. A crystal contact microphone made by Brush and marketed commercially as VM-1 crystal Vibromike, covered with a rubber boot, and whose dimensions are $\frac{1}{4}$ inch thick, $\frac{3}{4}$ inch wide and 2 inch long is suitable. The transducer is sealed in latex (e.g., GACO N-700) to protect it from corrosion. An audio frequency amplifier 12 designed for compactness (utilizing miniature tubes or transistors, printed circuitry, small batteries) is connected to transducer 10 and is supported on a belt around the swimmer's waist. A bone conduction electroacoustic transducer 14 is connected to the output of the amplifier and is supported on the swimmer's head; it may be the bone conduction type used with hearing aids. Where a bone conduction headset is worn over the ears, the swimmer's ears must be flooded or pressure on his ear drums must otherwise be equalized as by connecting an air tubing between the breathing apparatus and the ears. The mask over the swimmer's mouth is functionally related to the remainder of the apparatus through the medium of the swimmer.

Noise generated in the swimmer's body by blood circulation and other internal processes is negligible and does not interfere with voice communication.

Some binaural discrimination may be realized with the invention by using two transducers 10, two amplifiers and two transducers 14, and by covering at least the swimmer's head, with a pressure release material to restrict extraction of noise energy from the water by bone conduction in the skull. Binaural discrimination is limited by the fact that sound travels about 4.5 times faster in water than in air. The spacing between the two transducers 10 would have to be considerably greater than the spacing between the ears to realize significant binaural discrimination. The latter arrangement tends to render the apparatus cumbersome. Obviously many modifications and variations of the present invention are possible in the light of the above

teachings. It is therefore to be understood that within the scope of the appended claims the invention may be practiced otherwise than as specifically described.

We claim:

1. An improved method by which a plurality of underwater swimmers may continuously confer with one another while submerged in water comprising, at each swimmer, continuously intercepting and extracting from the water immediately adjacent the swimmer a fraction of any acoustic energy in the voice frequency range, amplifying the energy intercepted and extracted from the water adjacent the swimmer, continuously transferring the amplified voice frequency acoustic energy to the auditory nerve of the swimmer, continuously providing an air space around the nose and mouth of the swimmer for breathing purposes and to continuously enable the swimmer to speak into the air space concurrently while listening to voice frequency energy transferred to his auditory nerve.
2. An improved method by which a plurality of underwater swimmers may continuously confer with one another while submerged in water comprising, at each swimmer, continuously intercepting, extracting from the water, and amplifying a fraction of any voice frequency acoustic energy present in the water adjacent only the pelvic region of the swimmer so that the amplified voice frequently acoustic energy includes a minimum percentage of acoustic energy arising from limb movement and breathing of the swimmer, continuously transferring the amplified voice frequency vibrational energy to the auditory nerve of the swimmer, continuously blocking the water from the nasal passages of the swimmer, continuously providing an air space around the mouth of the swimmer to continuously enable the swimmer to speak into the air space concurrently with listening to voice frequency energy transferred to his auditory nerve, and coupling the acoustic energy of speech from the air space, head, neck and chest of the swimmer into the water for transfer to the other swimmers.
3. An improved method by which a plurality of underwater swimmers may continuously confer with one another while submerged in water comprising, at each swimmer, continuously intercepting and extracting from the water immediately adjacent the swimmer a fraction of any voice frequency acoustic energy present in the water adjacent the swimmer, continuously amplifying said voice frequency acoustic energy, continuously transferring the amplified voice frequency acoustic energy to the auditory nerve of the swimmer, continuously blocking the water from the nasal passages of the swimmer, continuously providing an air space around the mouth of the swimmer to continuously enable the swimmer to speak into the air space concurrently while listening to voice frequency energy transferred to his auditory nerve, supplying air for breathing to the swimmer, and transferring acoustic energy of speech generated by the swimmer from the air space around the mouth, from the head surface, neck surface and upper trunk surface of the swimmer to the water for transfer to the other swimmers.
4. Equipment for use by underwater swimmers in continuous conference voice communication with one another while swimming submerged, which comprises, for each swimmer, an underwater electromechanical transducer for voice frequencies, means mounting said transducer for support on the lower portion of the trunk of a swimmer's body, voice frequency sensitive means mounted for attachment to the swimmer's body, electrically connected directly to said transducer and continuously amplifying voice frequency electric currents from said transducer that are created by vibrations applied to said transducer from water in which the transducer is immersed, a headset electrically connected directly to said voice frequency means and transducing said amplified voice frequency currents into voice frequency vibrations applied to the head of the swimmer, and a mask to be worn by the

swimmer over his mouth and nose by which the swimmer may talk into the mask and through which a stream of air for breathing may be supplied, and create sound vibrations transmitted from the mask and the swimmer's body into the water in which the swimmer is immersed for transmission through the water to another swimmer, and the transducer will receive a minimum of mechanical vibrations due to movements of the swimmer's limbs in the water and the vibrations from the breathing air supply to the mask.

5. Equipment by which a plurality of persons while submerged in water may continuously confer with one another as they can in an air-filled room, which comprises, for each individual person, means for submergence in the water for receiving and amplifying voice frequency acoustic energy in the water adjacent thereto and without changing the frequency character of said energy, means supporting such means for attachment to such individual person, means for applying said amplified energy from said receiving means to the auditory nerve of that individual person, a face mask formed to fit such individual person's mouth to enable breathing when air is supplied thereto and for providing an air space in front of the mouth into which such individual person may speak at any time, and which mask can transfer some of the acoustic energy of speech in the air space into the sur-

rounding water for transmission to another submerged person.
